UNITED STATES PATENT OFFICE.

SAMUEL BERGER, OF NEWARK, NEW JERSEY.

DESIGN FOR A TOY.

Application filed May 17, 1924. Serial No. 9,635. Term of patent 14 years.

To all whom it may concern:

Be it known that I, SAMUEL BERGER, a citizen of the United States, and residing at the city of Newark, county of Essex, and State of New Jersey, have invented a new, original, and ornamental Design for a Toy, of which the following is a specification, reference being had to the accompanying drawing, forming a part hereof.

The figure is a perspective view of the toy embodying my new design.

I claim:

The ornamental design for a toy as shown.

SAMUEL BERGER.
